ANTIBURSTING DEVICE FOR PIPES

Walter D. Tickel, Norman, Okla.

Application June 11, 1943, Serial No. 490,534

4 Claims. (Cl. 138—28)

My invention relates to anti-bursting device for pipes, especially adapted to protect pipes, tubes, coils and the like against bursting due to freezing at low temperatures.

The principal objects of my invention are to provide a device of this character which is positive in action, simple and inexpensive in construction; new, novel and easily installed; which is strong, durable, reliable and of evident utility; which cannot easily get out of order and is efficient for the purposes for which it is intended; to provide a device for giving complete protection against internal expansion due to freezing; a device having anti-burst air pockets with male and female ends, the said air pocket being made in short units of any convenient length adapted to be coupled together and extended the full length of the pipe being protected against bursting; a device which may be inserted in heating radiator coils, pipe coils and the like which are subject to freezing, in which case the air pocket units may be secured together in sets by means of clamps; to provide a device, the said air pocket unit of which is substantially an ellipse in cross-section, made of identical halves seamed along their longitudinal edges, the male and female ends forming a tight fit and locked in place by means of lock fit projections and sockets, to provide a retrieving spring within the air pocket for returning the same to normal shape when the pipe or coil thaws out.

With these and other objects in view, my invention consists of the construction, novel features and combination of parts hereinafter more fully described, illustrated in the accompanying one-sheet drawing and pointed out in the claims hereto appended. Various changes in the form, proportion, size, shape, weight and minor details of construction, within the scope of my invention may be resorted to without departing from the spirit or broad principle of my invention or yielding any of its benefits.

In the accompanying drawing Figure 1 is a view showing a complete air pocket unit within a sectional part of a pipe and a fragment of a like unit at the male end thereof; Fig. 2 is an elevational view of a group of air pocket units clamped together; Fig. 3 is a longitudinal section of an air pocket unit; Fig. 4 is a perspective view of the retrieving spring; and Fig. 5 is a perspective view of the clamp.

In the following description like reference numbers designate like parts in all the figures, and it is to be understood that the drawing is to be interpreted as being illustrative and not restrictive.

One embodiment of my invention is shown as follows: The numeral 1 indicates a pipe in which is positioned my anti-burst air pocket unit 2 having a female end 2—a and a male end 2—d. I

provide a female end seal 3, shown in section at 3—a. Within the female end 2—a the projections 2—b are adapted to seat in the lock fit sockets 2—c on the male end and lock the anti-burst air pocket units 2 together as they are inserted in the pipe 1. As many of the said units 2 may be coupled together and inserted into the pipe 1 as are necessary to protect it against bursting. Spring 4 is positioned within unit 2 midway of its ends and is adapted to expand the said unit 2 to its original shape when the pipe 1 thaws out. The air in the said unit 2 will be compressed to equalize the increased volume within the pipe 1 due to freezing so that the said compressed air plus the energy stored in spring 4 will return the unit 2 to its normal shape and size. The said unit 2 may be made of any suitable material such as metal, plastic and the like. Unit 2 will be made rigid enough so as to be effected only slightly or not at all by the normal pressure of the liquid within pipe 1.

As shown in Figures 2 and 5 my anti-burst air pocket unit 2 (the sectional view Fig. 3 of which is shown on the line 3—3 of Fig. 2), may be grouped together in sets by means of clamp 5 and rivets 5—a for insertion in the coils of radiators or the like.

As can readily be understood from the foregoing specification, my anti-burst air pocket unit 2 can be made in various sizes and lengths to fit pipes as installed in the home, such as bath rooms, kitchens, laundries, etc. The householder is relieved of all worry and expense due to sudden unforeseen changes in temperature as my device is made a fixed part of the plumbing installation. The same is true for the plumbing pipes in hospitals, office buildings and similar structures. Untold damage and expense is incurred by bursting pipes in addition to the cost of protective means used to prevent the damage. As proof of the efficiency of my device the following experiment was carried out: Two identical pieces of pipe were filled with water and packed in dry ice, one protected with my device and the other without this protection. The ends of the pipes were of course closed with pipe caps. The unprotected pipe burst open along the seam. The protected pipe was undamaged.

My device, being elliptical in shape, offers little or no obstruction to the flow of fluid through a pipe, since it closely follows the inside curvature of the pipe as can best be seen in Fig. 1. It will be noted in Figures 1 and 3, the two halves being identical, only one die will be needed in the manufacture of my unit 2, which means a saving in the production of the same.

Having thus fully disclosed my invention what I claim as new and desire to secure by Letters Patent is:

1. In an anti-burst air pocket device compris-

ing a plurality of anti-burst air pocket units arranged in series, each unit having male and female ends, means on the said ends for locking the units together, internal means for restoring each unit to its original shape, the said units being made in various lengths so as to protect various runs of pipe without cutting any unit.

2. In a device of the class described, in combination, a plurality of anti-burst air pocket units arranged in series, each anti-burst air pocket unit being substantially elliptical in cross-section, conforming in part to the inside of the pipe in which it is placed, the units being made varying lengths to fit the various runs of pipe without cutting any unit, the said unit being formed of identical halves, means for uniting and hermetically sealing the said halves, male and female ends formed thereon, means for locking the units together and internal means for restoring the said unit to its original shape.

3. In a device of the class described, in combination, a plurality of anti-burst air pocket units arranged in series, each anti-burst air pocket unit being of substantially elliptical cross-section conforming in part to the inside curvature of the pipe it is protecting, the units of the series being made in varying lengths to fit various runs of

pipe without cutting any unit, the said unit being formed of identical halves, means for uniting and hermetically sealing the said halves, male and female ends formed thereon, internal sealing means within the female end, means for locking the said ends together and internal means for restoring the said unit to its original shape within the pipe which is being protected.

4. In a device of the class described, a plurality of anti-burst air pocket units arranged in series, each anti-burst air pocket unit being of substantially elliptical cross-section conforming in part to the inside curvature of the pipe in which it is placed, the units of the series being made in varying lengths to fit the various runs of pipe without cutting any unit, the said unit being formed of identical halves, means for uniting and hermetically sealing the said halves, male and female ends formed thereon, internal sealing means within the female end, means for locking the said ends together, clamp means for securing a plurality of the said series of units together for protecting radiators and the like and internal means for restoring each of the said units to its original shape within the radiator which is being protected.

WALTER D. TICKEL.
